ELMORE WILLIAM MENNINGER, OF LOS ANGELES, CALIFORNIA

FURRING CONSTRUCTION

Application filed December 10, 1925. Serial No. 74,470.

This invention relates to furring constructions involving a spacing element and means for connecting to the spacing element a member which may or may not itself be furred from the support. The invention is very useful in the construction of the interior and exterior surfaces of buildings of which the supporting structure is of masonry, whether the masonry be of mortar-joined blocks or of concrete cast in situ.

An object of the invention is to make provision for attaching a reinforcement foundation to a supporting structure in a manner to permit of totally embedding the reinforcement within a cementitious construction.

Another object is to make provision for increasing the ease of erecting the reinforcement foundation in position.

Another object is to provide a construction that when positioned in un-uniformly spaced relation in a structure, the spacing elements of the furring devices will admit of the reinforcement foundation being readily secured thereto. Thus, the erector can proceed expeditiously with the work of securing the reinforcement foundation in place without having had to predetermine the exact positions of said spacing elements.

A further object is to provide a construction in which the spacing element is integral with a metallic structural element, the combination being one form of the furring device.

This application is a continuation of my application, Serial No. 637,537, filed May 8, 1923, as to all matters common to the two applications.

The accompanying drawings illustrate several forms of the invention.

Figure 1 is a longitudinal perspective view of one form of furring device constructed in accordance with the provisions of this invention. The form member into which the furring device is driven is indicated in broken lines.

Fig. 1a is a sectional elevation on the line indicated by 1a—1a, Fig. 1.

Fig. 2 is an elevation, partly in section, showing the furring device of Fig. 1 in place in its supporting structure, the members engaged by the device also being shown.

Fig. 3 is a longitudinal perspective view of a second form of furring device constructed in accordance with the provisions of this invention.

Fig. 3a is a sectional elevation on the line 55 indicated by 3a—3a, Fig. 3.

Fig. 4 is a perspective view of a third form of furring device constructed in accordance with the provisions of this invention, a fragment of the support with the spacing element 60 only being shown.

Fig. 4a is a sectional elevation on the line indicated by 4a—4a, Fig. 4.

Fig. 5 is a longitudinal view of one form 65 of locking member employed with the furring device.

Fig. 6 is a longitudinal view of a second form of locking member.

Fig. 7 is a longitudinal view of a third form 70 of locking member.

Describing first the form of the invention shown in Figs. 1, 1a and 2, and referring more particularly at present to Fig. 1, the furring device illustrated is especially useful where its supporting structure is of masonry construction such, for example, as a cement-concrete wall. One of the members used in forming the wall is indicated at 11 and comprises a wooden plank. The furring device, indicated in general by the character 12, is 80 driven into said member 11 so as to temporarily support the furring device while the concrete is being poured to form the wall. Only one of the wooden members 11 is shown in the drawings as the construction of forms 85 of this character is well understood in the art relating to cement-concrete construction.

The furring device is constructed as follows: The support or shank 13 of the furring device is preferably in the form of a screw blade so as to more firmly secure the furring device against pulling out of the supporting structure 14, shown in Fig. 2. The outer end of the shank 13 is squared off or, in other words, approximately at a right 95 angle to the longitudinal axis of the shank to form a head which may be struck by a hammer for effecting driving of the furring device into a wooden form member. The projecting furring portion or straight blade or 100

prong 15 of the furring device is preferably pointed at its tip 16 and is reduced in thickness at the tip so that the furring device can be readily driven into the member 11, when 5 such member is employed.

The shank 13 is of a width preferably greater than the width of the blade 15, forming an offset portion at the junction with the blade 15 or, in other words, terminates in a 10 shoulder or shoulders 17 from which the blade 15 extends and which, contacting with the face of the member 11 when the furring device is driven therein, limits the driving depth of said furring device, thereby predetermining 15 the distance that the furring device projects from the support 14. The object of this is to give uniformity to the furring. The shoulders 17 also function to indicate the depth of setting of the furring device in the 20 mortar joint of a construction built of blocks, as brick or tile.

The furring portion 15 is provided with an eye or opening 18 designed, when desired, to receive one of the wires 19 of a reticulated 25 member indicated in general by the character 20. In Fig. 2 none of the wires 19 is engaged in the eye 18 but, in order that the wire 19 may be placed in the eye 18, a portion 21 of the wall of the eye 18 is partially detached by 30 cutting into the main body of the furring portion 15, so that the portion 21 can be readily removed to produce a relatively wide slot through which the wire 19 can be passed into the eye 18. In the instance illustrated in Fig. 35 1, the portion 21 is partially detached by providing a kerf 22, extending all the way through the furring portion 15, and another kerf 23 which extends but part way through the furring portion 15. Thus, by striking the portion 21, for instance, said portion may be 40 detached to admit the wire 19. After the wire 19 is placed in the eye 18, the erector will strike up the tip 16 so as to contract the slot made by the removal of the portion 21, thus 45 to prevent the wire 19 from escaping from the eye 18. However, in Fig. 2, instead of the wire 19, I have shown a locking member or pin 26 in the eye 18 extending along the outer face of the reticulated member. This 50 locking pin 26 is shown in Fig. 5 and other forms thereof are shown at 26a, 26b, in Figs. 6 and 7, respectively. The locking pin 26, 26a or 26b, as the case may be, serves the same purpose as the wire 19 in locking the reticulated member to the furring portion 15.

In order that the member 19 or 26, as the case may be, may be securely clamped in the eye 18, I prefer to edge, tooth or notch the wall of the eye as indicated at 261 so that, 60 when the eye is contracted, the wall will firmly grip the wire 19 or pin 26.

When the locking pin 26, 26a or 26b is employed, the reticulated member 20 may be furred a predetermined distance from the 65 support by dropping another of the locking

pins into a notch or eye 262 formed in the upper edge of the furring portion 15 or by inserting the same through an eye 263 near the lower edge of the furring portion 15. The spacing of the eye 18 from the notch 262 or eye 263 is substantially equal to the thickness of the reticulated member. 70

It may be desirable, in some instances, especially when the mesh of the reticulated member 20 is comparatively large, to employ a 75 backing 24 to prevent the cementitious material 25 applied to the reticulated member from falling away from the rear face of said reticulated member. If desired, the backing may be constructed in a manner and of materials that will give to it the necessary characteristics to make it a thermal or/and sound insulator. When such backing 24 is utilized, I prefer to definitely space it from the supporting structure 14 and, in this instance, do so by employing another of the locking pins 26 seated in a notch or eye 27 in the upper edge of the furring portion 15. The pin 26 and notch 27 predetermine the thickness of the cementitious material lying 80 between the reticulated member 20 and the backing 24, and also the spacing of the backing 24 from the supporting structure. 85

In some instances it may be desirable to hold the backing 24 against movement toward the reticulated member 20 during the operation of applying the cementitious material 25 and, accordingly, I provide in the furring portion 15 an eye 28 to receive another of the locking pins 26, 26a or 26b. The spacing 90 of the notch 27 and eye 28 substantially corresponds to the thickness of the backing 24. 95

It may be desirable, in some instances, to employ a sound or/and thermal insulation 29 along the supporting structure 14 rearward of the backing 24 and said insulation may be spaced from the backing to form a dead air space 30. To hold the insulation 29 in place I may employ another of the locking pins 26, 26a or 26b seated in a notch or eye 31 in the upper edge of the furring portion 15, or the locking pin may be inserted in an eye 311 near the lower edge of the blade 15. The eye 311 and notch 31 are spaced from the supporting structure 14 a distance substantially equal to the thickness of the insulation 29. 100

In some instances, the furring device 12, or at least the blade 15, will be coated, as indicated at 37 in Fig. 1a, with a suitable resinous material or other coating that is both adhesive and yielding to the touch and resistant to chafing and moisture, possessing such insulating qualities as to protect, in some instances, the blade 15 of the furring device 12 115 and the other metallic members employed in the structure, against metallic contact and frequent consequent oxidation, at points where said blade 15 engages said other metallic members, and avoid or limit, in some instances, 120

stances, the transmission of sound waves, between members of the structure, ordinarily transmitted by the blade 15 of the furring device 12. The material is preferably applied in two coats, in which instance one coat will be, preferably, soft and one coat will be, preferably, hard. The object of this is to secure a coating possessing a relative fixedness combining a certain pliability. I have discovered, therefore, a novel application of a coating material especially useful with furring constructions of the type herein described.

In view of my discovery described above, I preferably form my furring device having a support or blade shank for embedding in masonry, of corrosion-resisting metal, since the coating as aforesaid of metallic connecting members such, for example, as the blade 15 of my furring device, possessing highly corrosive-resistant properties, engaging another or other metallic members such, for example, as shown in Fig. 2 of the drawings, formed of metals generally used for such members, produces, in addition to the other qualities possessed by the coating treatment, a practically everlasting structure.

The invention operates as follows: Assuming that the member 11 is in place, the erector will drive the furring device into the member 11 until the shoulders 17 bear against said member as in Fig. 1. The pouring of the concrete in the forms will then be performed as is well understood in the art relating to buildings and other structures, thus embedding the shank 13 of the furring device in the concrete structure 14, after which the forms will be removed leaving the furring portion 15 projecting from the wall or, if the supporting structure is constructed of blocks, during the laying up of the same, the mason will lay the furring device with the shank 13 embedded in one of the mortar joints between the blocks, with the shoulders 17 flush with the outer face of said blocks.

It may be desirable, in some instances, to provide a dead air space rearward of the backing 24. Then, if in the dead air space 30 an insulation is to be provided, the erector will proceed to place the insulation 29 and lock the same in position by inserting the pin 26 in the eye 31. He will then place a pin 26 in the eye 27 and will place the backing 24 against said pin. He will then lock the backing 24 in place by inserting one of the pins 26 in the eye 28.

The erector will then proceed to place the reticulated member 20 in position, first placing one of the pins 26 in the eye 262, then positioning the reticulated member against said pin and, finally, placing one of the pins 26 in the eye 18. He will then strike the tip 16 to close the eye 18 upon the pin in said eye.

The cementitious material will then be applied to the reticulated member and forced

through the mesh thereof and against the backing 24, thus completing the construction.

Now referring more particularly to Figs. 3 and 3a, as illustrating a different form of the furring device, the parts thereof that correspond in function to those described above, are indicated by the same reference characters, with the addition of the letter a. In this particular instance instead of the eye 18, the tip 16a is provided with a V-like eye 18a, and the walls of said eye are preferably edged, notched or toothed, as indicated at 261a.

The shank 13a is L-shape and is provided with orifices 32 into which the cementitious material passes, so as to aid in anchoring the furring device in the support, the flange 33 also aiding in the anchoring.

Now the referring more particularly to Figs. 4 and 4a, the parts that functionally correspond with those described in connection with Fig. 1 are indicated by the same reference characters, with the addition of the letter b. The furring device, in this instance, comprises a metallic structural member consisting of a support 13b and a spacing element or furring portion 15b. The support 13b corresponds to the supports indicated at 13, 13a in the drawings, but it differs from the supports 13, 13a in that the spacing element or furring portion 15 is punched therefrom. In the instance illustrated, the support 13b has flanges or walls 34 at an angle to each other to form a channel member, and punched from one of said walls is an ear, blade or prong, thus forming the furring portion 15b and the orifice 36. In this instance, the furring portion 15b projects at a right angle from one of the walls 34 of the support 13b and extends beyond the plane of said wall. It will be readily understood that the furring portion 15b may be punched in part from two adjoining walls of the support 13b and that it may extend longitudinally of the support and, also, that it may be twisted, if desired.

The wall of the eye 18b may be notched or toothed and contracted around any member inserted in said eye by striking against the tip 16b, since there is a kerf 22b communicating with the eye. The kerf 22b is spread sufficiently to admit of a strand of a reticulated member to pass through the slot thus made into the eye. An eye 28b is provided for receiving a locking pin, in the manner described above for the eye 28 and locking pin 26, in order to lock in place a backing similar to the backing 24.

Other eyes or notches, if desired, may be provided in the furring device 12b to correspond with those described above in connection with Figs. 1, 2 and 3. This will be readily understood without further illustration since it is mere duplication; also, it will be readily understood that it may be desirable, in some instances, to provide the locking

members securing the members 20, 24 and 29 in place, continuous from furring device to furring device, in order that the locking members may also firmly engage the members 20, 24 and 29 in place at points between the furring devices, when the furring devices are relatively widely separated.

I claim:

1. The combination with a support, of a furring device projecting from said support and provided with an opening, a reticulated member through which the furring device projects, a backing between the reticulated member and the support, and means on the furring device to hold the backing spaced a predetermined distance from the reticulated member.
2. The combination with a support, of a furring device projecting from said support and provided with an opening, a reticulated member through which the furring device projects, a backing between the reticulated member and the support, means on the furring device to hold the backing spaced a predetermined distance from the reticulated member, an insulation between the backing and the support, and means on the furring device to hold the insulation a predetermined distance from the backing.
3. A furring device having a screw shank terminating in a shoulder, a blade extending from the shoulder and pointed at its tip and provided with an opening for receiving a locking or other member.
4. A furring device having a shank and a blade, a shoulder at the junction of the shank and blade, the tip of the blade being pointed for driving and provided with an opening to receive a locking or other member.
5. A furring device having a shank and a blade, a shoulder at the junction of the shank and blade, the blade having an eye to receive a locking or other member, the wall of the eye being corrugated, and said blade having a slot opening from the eye to one of the edges of the blade.
6. A furring device having a shank and a blade, a shoulder at the junction of the shank and blade, the blade pointed at its tip and having a slot in its tip.
7. The combination comprising a support with a prong projecting therefrom, the prong having an opening, a reticulated member through which the prong projects and secured thereto, a backing between said support and the reticulated member, and means on the prong to hold the backing spaced a predetermined distance from the support.
8. The combination comprising a support with a prong projecting therefrom, the prong having an opening, a reticulated member through which the prong projects and secured thereto, a backing between said support and the reticulated member, means on the prong to hold the backing spaced a predetermined distance from the support.

mined distance from the reticulated member, and an insulation between said support and the backing.

9. A construction comprising a support and a blade prong in combination, the prong having an opening which extends to the edge thereof, said opening being provided with a notched wall to grip a locking or other member when secured therein.

10. A furring device comprising a shank and a blade in combination, the blade pointed at its end for driving and provided with an opening for receiving a locking or other member.

11. A furring device comprising a shank and a blade in combination, the blade pointed at its end and provided with a slot having its wall notched and opening into the tip of said blade.

12. A furring device comprising a deformed shank and a blade connected with the shank and having an irregular opening in its end extending to the tip of said blade for receiving a locking or other member.

13. A furring device comprising a shank provided with means to secure it against pulling out of cementitious material, and a blade connected with the shank and having an opening for receiving a locking or other member, the shank at the junction with the blade forming an offset portion extending substantially the length of the shank.

14. The combination comprising a support with an integral prong projecting therefrom, the prong having an opening, a reticulated member through which the prong projects and secured thereto, a backing between said support and the reticulated member, and means on the prong to hold the backing spaced a predetermined distance from the reticulated member.

15. The combination comprising a support, and a prong pointed at its tip and having an opening reduced inwardly from the edge of the prong so as to be substantially V-shaped.

16. A furring device comprising a shank provided with means to anchor it in cementitious material and a blade connected with the shank and having its tip pointed for driving and having an opening for receiving a locking or other member.

17. A furring device comprising a shank provided with means to anchor it in cementitious material and a blade having its tip pointed for driving and provided with an opening for receiving a locking or other member, and a shoulder at the junction of the shank and blade.

18. A furring device comprising a shank provided with means to anchor it in cementitious material and a blade connected with the shank and having an opening provided with a notched wall to grip a locking or other member when secured therein.

19. The combination comprising a shank

and a blade, and means indicating the junction of the shank and blade, the blade being pointed at its tip and having an opening provided with a notched wall to grip a locking or other member when secured therein.

20. A furring device comprising a shank and a blade in combination, the blade having its tip pointed for driving and having an opening provided with means to grip a locking or other member when secured therein.

21. The combination comprising a support, and a prong having an eye near its end and a slot extending from the eye and opening into the tip of the prong for receiving a locking or other member.

22. A furring device comprising a shank provided with means to anchor it in cementitious material and a blade connected with the shank and having an eye near its end and a slot extending from the eye and opening into the tip of the blade for receiving a locking or other member.

23. The combination comprising a shank and a blade and means indicating the junction of the shank and blade, the blade being pointed at its tip and having an eye near its end and a slot extending from the eye and opening into the tip of the blade for receiving a locking or other member.

24. The combination comprising a shank, and a blade having its tip pointed and having an eye near its end and a slot extending from the eye and opening into the tip of the blade for receiving a locking or other member.

25. The combination comprising a support, and a prong having a slot opening into the tip thereof whose wall is provided with means to grip a locking or other member when secured in the slot.

26. A furring device having a shank, a blade, and means indicating the junction of the shank and blade, the tip of the blade being pointed for driving and provided with an opening to receive a locking or other member.

27. The combination comprising a support, and a prong having an opening reduced inwardly from the edge thereof so as to be substantially V-shaped, to receive and retain a portion of a reticulated or other member secured thereto.

28. The combination comprising a support of deformed shape, and a prong having means to receive and retain a portion of a reticulated or other member secured thereto in spaced relation to the support and extending substantially transversely to said prong, said prong extending to the outer face of the reticulated or other member when engaged therewith, the support at the junction with the prong forming an offset portion extending substantially the width of the support.

29. The combination comprising a support and a prong, the support at the junction with the prong forming a shoulder projecting at

right angles away from the edge of the prong and extending substantially through the width of the support, and the prong having an opening for receiving a locking or other member.

30. This combination comprising a support and a prong projecting therefrom, the prong having an opening whose wall is corrugated to grip a locking or other member when secured therein.

31. The combination comprising a support and a prong projecting therefrom, the support being of deformed shape, and the prong having an opening whose wall is corrugated to grip a locking or other member when secured therein.

32. The combination comprising a support and a prong projecting therefrom, the support being of deformed shape, and the prong having an eye near its end and a slot extending from the eye and opening into the tip of the prong for receiving a locking or other member.

33. A furring construction comprising a support and a prong in combination, the support having a blunt outer end and means to secure it against pulling out of cementitious material, and the prong having its tip pointed for driving and provided with means to receive and retain a portion of a reticulated or other member secured thereto, and which prong extends to the outer face of the reticulated or other member when engaged therewith.

34. The combination comprising a support, a prong, and a shoulder at the junction of the support and prong, the prong having an opening whose wall is notched to grip a locking or other member when secured therein.

35. The combination comprising a support, a prong, and a shoulder at the junction of the support and prong, the prong having an eye near its end and a slot extending from the eye and opening into the tip of the prong for receiving a locking or other member.

36. The combination comprising a support, a prong, and a shoulder at the junction of the support and prong, the prong having a slot opening into the tip thereof whose wall is provided with means to grip a locking or other member when secured in the slot.

37. The combination comprising a support, a prong, and a shoulder at the junction of the support and prong, the prong being provided with an opening reduced inwardly from the edge thereof so as to be substantially V-shaped.

38. The combination comprising a support provided with means to secure it against pulling out of cementitious material, and a prong connected with the support and pointed at its end and having an opening whose wall is notched to grip a locking or other member when secured therein.

39. The combination comprising a support

provided with means to secure it against pulling out of cementitious material, and a prong connected with the support and pointed at its tip and having a slot in the tip to receive and retain a portion of a reticulated or other member secured thereto.

40. The combination comprising a support provided with means to secure it against pulling out of cementitious material, and a prong connected with the support and pointed at its tip and provided with an opening reduced inwardly from the edge of the prong so as to be substantially V-shaped.

41. The combination with cementitious material comprising a support with a prong projecting therefrom, the prong having an opening in its outer end, a reticulated member through which the prong projects and secured thereto, a backing or insulation between the support and the reticulated member, and attachable means on the prong engaging the backing or insulation and spaced a predetermined distance from the reticulated member.

42. The combination with cementitious material comprising a support with a prong projecting therefrom, the prong having an opening in its outer end, a reticulated member through which the prong projects and secured thereto, a backing or insulation between the support and the reticulated member, and separate means to hold the backing or insulation and spaced a predetermined distance from the reticulated member.

43. The combination with cementitious material, comprising a support with a prong projecting therefrom, the prong having an opening in its outer end, a reticulated member through which the prong projects and secured thereto, a backing or insulation between the support and the reticulated member, and means to hold the backing or insulation spaced a predetermined distance from the support.

45. Signed at Los Angeles, California, this 4th day of December, 1925.

ELMORE WILLIAM MENNINGER.
